FRANK R. CHESTER, OF ASBURY PARK, NEW JERSEY.

AMUSEMENT APPARATUS.

1,410,371.

Specification of Letters Patent. Patented Mar. 21, 1922.

Application filed October 15, 1920, Serial No. 417,160.

To all whom it may concern:

Be it known that I, FRANK R. CHESTER, a citizen of the United States, and a resident of Asbury Park, in the county of Monmouth and State of New Jersey, have invented a new and Improved Amusement Apparatus, of which the following is a full, clear, and exact description.

The object of the invention is to provide 10 a new and improved amusement apparatus more especially designed for use in pleasure resorts, exhibition grounds, fairs and other places of amusement, and arranged to enable a number of players to participate at 15 the time and to provide a rather unexpected and startling effect at the end of each play or game.

Another object is to require considerable skill on the part of a player to successfully 20 actuate the apparatus in the shortest time to win the game.

With these and other objects in view, the invention consists of certain novel features of construction as hereinafter shown and 25 described and then specifically pointed out in the claims.

A practical embodiment of the invention is represented in the accompanying drawings forming a part of this specification, in 30 which similar characters of reference indicate corresponding parts in all the views.

Figure 1 is a cross section of the improved amusement apparatus;

Figure 2 is a fragmentary front elevation of the same;

Figure 3 is an enlarged sectional plan view of the mouth of a toy balloon held in a supporting clamp, the section being on the line 3-3 of Figure 1;

Figure 4 is an enlarged sectional side elevation of the controlling valve for the fluid pressure of the actuating means; and

Figure 5 is a cross section of a modified form of the improved amusement apparatus.

The players range one alongside the other in front of a counter 10 or a similar structure, and each of the players manipulates a handwheel 11 secured to the front end of 50 a shaft 12 journaled in suitable bearings 13 and 14 arranged on the upper portion of the counter 10, as plainly shown in Figure 1. The rear end of the shaft 12 is provided with a crank 15 connected by a 55 pitman 16 with the piston rod 17 of a piston 18 reciprocating in the cylinder 19 of

an ordinary air pump of any approved construction and mounted on the counter 10. The rear of the counter 10 is provided with a support 20 on the top of which are mounted 60 holders 21 corresponding in number to the wheels 11 and disposed opposite the same, and each clamp or holder 21 is adapted to clamp and close the mouth 22 of a hollow fragile object 23 such as an inflatable 65 toy balloon supported in inflated condition on the corresponding clamp 21. Each fragile object 23 is adapted to be pierced by a piercing member 24 controlled by an actuating mechanism actuated by fluid pressure such as compressed air, the flow of 70 which is controlled by the corresponding handwheel 11. For this purpose the following arrangement is made:

The cylinder 19 is connected by an outlet pipe 25 with a cylinder 26 connected by a pipe 27 with a second cylinder 28 so that the compressed air from the air cylinder 19 of the air pump supplies both cylinders 26 and 28 with compressed air to raise the 80 pistons 29 and 30 mounted in the said cylinders 26 and 28. The piston 30 is pressed in a downward direction by a spring 31, and the piston rod 32 of the piston 30 terminates in a cut-off valve 33 mounted to 85 slide in a valve casing 34 arranged in a pipe 35 connecting a compressed air tank 36 with a cylinder 37 mounted to swing on a pivot 38 arranged on top of a support 39 forming part of the counter 10. In the 90 cylinder 37 slides a piston 40 having its piston rod 41 terminating in a pawl 42 engaging ratchet teeth 43 formed on a bar 44 carrying the piercing element 24 and mounted to slide in bearings 45 and 46 at 95 attached to the supports 29 and 30, respectively. The cylinder 37 is normally held in the inclined position shown in Figure 1 by a spring 47 connecting the cylinder 37 with the support 39. On the top of the cylinder 100 37 is mounted a spring-pressed dog 48 engaging the ratchet teeth 43 to hold the bar 44 against accidental downward movement as long as the cylinder 37 is held in the inclined position shown in Figure 1.

When a player turns the handwheel 11 the piston 18 of the air pump is actuated to force compressed air from the cylinder 19 by way of the pipe 25 into the cylinder 26 and by way of the pipe 27 into the cylinder 28 to 110 lift the piston 30 against the tension of the spring 31. In lifting the piston 30 the valve

33 moves into an open position to allow compressed air to flow from the tank 36 into the cylinder 37 to move the piston 40 upward and thus cause the pawl 42 to lift the bar 44 carrying the piercing member 24. As the compressed air in the cylinder 28 accumulates, the valve 33 moves into a closed position and consequently the supply of compressed air from the tank 36 to the cylinder 10 37 is shut off, and as both cylinders 28 and 37 are provided with bleed holes 50 and 51 sufficient air escapes to allow the pistons 30 and 40 to move downward. The downward movement of the piston 40 causes the pawl 15 42 to engage the next following tooth, and when the piston 40 is again pushed upward another upward movement is given to the bar 44 and the piercing member 24. Thus by the arrangement described an upward step 20 by step movement is given to the bar 44 and its piercing element 24 to move eventually the piercing element 24 into piercing contact with the inflated balloon 23, to pierce the same and allow the latter to collapse.

25 The piston 29 in the cylinder 26 is pressed downward by a spring 60, and the piston rod 61 of the piston 29 is provided with an arm 62 to which one end of a rope, cable, or other flexible connection 63 is attached.

30 This flexible connection 63 passes under guide pulleys 64, 65, 66 and connects at its other end with the cylinder 37 to swing the latter from the inclined position shown in Figure 1 to the right to disengage the pawl 35 42 and the dog 48 from the ratchet teeth 43 of the bar 44 at the time the piston 29 is moved upward by excessive air pressure accumulating in the lower portion of the cylinder 26. It will be noticed that when this 40 takes place the bar 44 drops to lowermost position and its upward movement again begins only after the return of the cylinder to the normal position shown in Figure 1 and the lifting of the piston 30 to move the 45 valve 33 into open position. From the foregoing it will be seen that by the arrangement described a step by step movement is given to the bar 44 on the player turning the handwheel 11, but, in case the 50 handwheel 11 is turned too fast and too much air is forced by the air pump into the cylinders 26 and 28, then the upward feeding movement given to the bar 44 ceases and the bar is allowed to drop on swinging the 55 cylinder 37 from normal position to the right, as above explained.

In playing the game, the players turn the handwheels 11 with a view to move the piercing elements 24 into piercing engagement with the inflated balloons 23, but by controlling the flow of air from the tank 36 to the cylinder 37 by the valve 33 an uncertain element is provided to retard the movement of the bar 44 in case the player turns the 60 handwheel too fast or too slow, and a fur-

ther uncertain element is provided by the releasing device for the bar 44 to release the latter and allow the same to drop in case a player turns the handwheel 11 too fast and thereby forces excessive compressed air into 70 the cylinder 26. It is understood that the player who is able to pierce the balloon 23 in the shortest time is the winner. It is evident that the playing of the apparatus affords considerable amusement to the players as well as to the onlookers and a startling 75 effect is provided on the deflating of the balloon incident to the piercing thereof.

In practice, the clamp or holder 21 is provided with a central eyelet 60 adapted to 80 engage a stud 61 held on the support 20 to allow convenient removal of the clamp and opening of the same for disengagement with the mouth 22 of the bursted balloon, and replacing the latter by a new inflated balloon. Thus the operator in charge of the amusement apparatus can quickly and conveniently replace a pierced deflated balloon by an inflated balloon prior to starting another game.

90 In the modified form shown in Figure 5, the piercing element 70 is stationary while the fragile object 71, that is, an inflated balloon, is movable towards the piercing element to be pierced by the latter. For the purpose mentioned, the piercing element 70 is attached to posts 72 arranged on the top of an inclined guideway 73 on which is mounted to slide a carriage 74 supporting a pin 75 adapted to be engaged by a clamp or holder 76 carrying the inflated balloon 71, the same as the clamp or holder 21. To the carriage 74 is secured one end of a rope, cable or other flexible connection 80 extending over a guide pulley 81 and winding on a 100 drum 82 mounted to rotate loosely on a shaft 83 journaled in suitable bearings 84 and 85, of which the bearing 85 is attached to the front of the counter or similar structure 86. On the outer end of the shaft 83 110 is secured a handwheel 87 under the control of a player to rotate the shaft 83 and with it the friction disks 88 and 89 and the drum 82 to wind up the flexible connection 80 with a view to draw the carriage 74 and the balloon 115 71 towards the piercing element 70 to pierce the balloon 71 and thus allow air to escape therefrom. On the shaft 83 is secured a friction disk 88 engaged by a friction disk 89 forming part of the drum 82 and held normally in engagement with the friction disk 88 by a spring 90 coiled on the shaft and bearing against the inner end of the drum 82. The spring 90 abuts against a collar 91 secured to the shaft 83. The rear end of the shaft 83 is 125 provided with a crank 95 connected by a pitman 96 with the piston rod 97 of a piston 98 mounted to reciprocate in the cylinder 99 of an air pump of usual construction. The air pump cylinder 99 is connected by 130

a pipe 100 with a cylinder 101 similar to the cylinder 28 and provided with a bleed hole 102. In the cylinder 101 is mounted a piston 103 pressed on by a spring 104 and 5 having a piston rod 105 provided with a valve 106 similar to the valve 32 and sliding in a valve casing 107 arranged in a pipe 108 connecting a compressed air tank 109 with a cylinder 110. In the cylinder 110 is mounted 10 a piston 111 having its piston rod 112 connected with a shifting lever 113 engaging an annular groove 114 in the hub 115 of the friction disk 89. It will be noticed that when the valve 106 moves into 15 open position compressed air from the tank 109 can pass by way of the pipe 108 into the cylinder 110 to move the cylinder 110 to the right thus imparting a swinging movement to the shifting lever 113 to move the 20 friction disk 89 out of engagement with the friction disk 88 thus interrupting the winding up of the flexible connection 80 for the time being, that is, until the supply of air from the cylinder 99 of the air pump to the 25 cylinder 101 decreases, and the air pressure in the cylinder decreases by the escape of the air through the bleed hole 102 to allow the valve 106 to move into closed position. When this takes place the air from the tank 30 109 to the cylinder 110 is shut off and the friction disk 89 returns to normal position by the action of the spring 90 to cause the drum 82 to rotate on the player rotating the handwheel 87. It will be noticed that by 35 the arrangement described similar uncertain elements are provided as above described in reference to the apparatus shown in Figures 1 and 2, and hence considerable skill is required on the part of a player to successfully move the balloon into engagement 40 with its piercing element 70 in the shortest time to win the game.

Having thus described my invention, I claim as new and desire to secure by Letters Patent:—

1. An amusement apparatus, comprising a fragile object, demolishing means, actuating means for moving the said object and the said demolishing means into contact one 50 with the other to demolish the said object, and a hand-operated controlling means connected with the said actuating means and provided with automatic governing devices governing the movement of the said actuating means.

2. An amusement apparatus, comprising a fragile object, external demolishing means for demolishing the same, and a hand-operated controlling means provided with automatic controlling devices to govern the demolishing effect of the object by the said external demolishing means.

3. An amusement apparatus, comprising an inflatable toy balloon, piercing means 65 adapted to pierce the said balloon, actuating

means moving the said balloon and the said piercing means into piercing relation one to the other to deflate the balloon, and a hand-operated controlling means connected with the said actuating means. 70

4. An amusement apparatus, comprising an inflatable toy balloon, piercing means adapted to pierce the said balloon, actuating means moving the said balloon and the said piercing means into piercing relation one to 75 the other to deflate the balloon, and a hand-operated controlling means connected with the said actuating means, and provided with automatic governing devices governing the movement of the said actuating means. 80

5. An amusement apparatus, comprising an inflatable toy balloon, piercing means adapted to pierce the said balloon, actuating means moving the said balloon and the said piercing means into piercing relation one to 85 the other to deflate the balloon, a hand-operated controlling means connected with the said actuating means, and fluid pressure governing means connected with the said actuating means to automatically control 90 the movement thereof.

6. An amusement apparatus, comprising an inflatable toy balloon, piercing means adapted to pierce the said balloon, actuating means moving the said balloon and the 95 said piercing means into piercing relation one to the other to deflate the balloon, a hand-operated controlling means connected with the said actuating means, fluid pressure governing means connected with the said actuating means to automatically control the 100 movement thereof, and means for actuating the said fluid pressure governing means by the said hand-operated controlling means.

7. An amusement device, comprising an 105 inflatable toy balloon, piercing means adapted to pierce the said balloon, actuating means moving the said balloon and piercing means into piercing relation one to the other to pierce the balloon, fluid pressure means for the said actuating means, and a hand-operated controlling means controlling the said fluid pressure means. 110

8. An amusement device, comprising an 115 inflatable toy balloon, means for holding the said balloon in inflated position, a slidable bar having a piercing point adapted to pierce the said balloon, actuating means imparting a step by step movement to the said bar, and a hand-operated controlling means for the 120 said actuating means.

9. An amusement device, comprising an 125 inflatable toy balloon, means for holding the said balloon in inflated position, a slidable bar having a piercing point adapted to pierce the said balloon, actuating means imparting a step by step movement to the said bar and including fluid pressure means, a hand-operated air pump, and a valve controlling the flow of the air from the said 130

fluid pressure means to the actuating means, the said valve being controlled by compressed air from the air pump.

10. An amusement device, comprising an 5 inflatable toy balloon, means for holding the said balloon in inflated position, a slideable bar having a piercing point adapted to pierce the said balloon, actuating means for imparting a step by step movement to the 10 said bar and including fluid pressure means, a hand-operated air pump, a valve controlling the flow of the air from the said fluid pressure means to the actuating means, the said valve being controlled by compressed air from the air pump, and a releasing device for the said actuating means and controlled by compressed air from the said air pump.

11. An amusement device, comprising an 20 inflatable toy balloon, demolishing means for the said balloon, a hand-operated air pump, two connected cylinders having spring-pressed pistons and of which one is connected with said air pump, the said piston of one 25 of the cylinders controlling the said demolishing means, and a releasing device for the said demolishing means and controlled by the piston in the other cylinder.

12. An amusement apparatus including a 30 destructible object, demolishing means adapted to effect a destruction of said object, manually operable means for effecting a con-

tact between said object and said demolishing means, and controlling means connected to said operating means for varying the 35 time required to effect said contact.

13. An amusement apparatus including in combination a balloon, means for supporting said balloon, demolishing means for said balloon, and operating means for causing contact to be effected between said balloon and demolishing means.

14. An amusement apparatus including a balloon and means for supporting the same, demolishing means including a piercing element disposed adjacent to said balloon, and an operating means for moving the wall of the balloon and piercing element with respect to each other whereby to effect a contact between said piercing element and wall 50 to destroy the balloon.

15. An amusement apparatus including a balloon, a demolishing member, the balloon and member being movable relatively one to the other, and means for bringing the 55 said member and balloon forcibly into contact with each other.

16. An amusement apparatus including a balloon, fixed means for supporting the balloon, demolishing means comprising a piercing element, and operating means for moving the piercing element into contact with the balloon to pierce the same.

FRANK R. CHESTER.
